United States Patent

Des. 236,354
Patented Aug. 19, 1975

236,354

LOCKING DEVICE FOR TELEPHONE DIALS

Carmelo Rodriguez, 35—41 Fort Washington Ave.
(Apt. 1A), New York, N.Y. 10032

Filed Mar. 29, 1974, Ser. No. 456,023

Term of patent 14 years

Int. Cl. D8—07; D14—03

U.S. Cl. D26—14 A

Fig. 1.

Fig. 2.

Fig. 3.

Fig. 4.

FIG. 1 is a rear prospective view of a locking device for telephone dials, showing my new design;

FIG. 2 is a side elevational view thereof;

FIG. 3 is a front view thereof; and

FIG. 4 is a bottom plan view thereof.

I claim:

The ornamental design for a locking device for telephone dials, as shown.
